FIG. 3 is a rear side view of FIG. 1 thereof;

FIG. 4 is a right side view of FIG. 1 thereof;

FIG. 5 is a left side view of FIG. 1 thereof;

FIG. 6 is a top side view of FIG. 1 thereof;

FIG. 7 is a bottom side view of FIG. 1 thereof;

FIG. 8 is perspective view of a second embodiment of a label sheet assembly with raised tactile features;

FIG. 9 is a front side view of FIG. 8 thereof;

FIG. 10 is a rear side view of FIG. 8 thereof;

FIG. 11 is a right side view of FIG. 8 thereof;

FIG. 12 is a left side view of FIG. 8 thereof;

FIG. 13 is a top side view of FIG. 8 thereof;

FIG. 14 is a bottom side view of FIG. 8 thereof;

FIG. 15 is perspective view of a third embodiment of a label sheet assembly with raised tactile features;

FIG. 16 is a front side view of FIG. 15 thereof;

FIG. 17 is a rear side view of FIG. 15 thereof;

FIG. 18 is a right side view of FIG. 15 thereof;

FIG. 19 is a left side view of FIG. 15 thereof;

FIG. 20 is a top side view of FIG. 15 thereof;

FIG. 21 is a bottom side view of FIG. 15 thereof;

FIG. 22 is perspective view of a forth embodiment of a label sheet assembly with raised tactile features;

FIG. 23 is a front side view of FIG. 22 thereof;

FIG. 24 is a rear side view of FIG. 22 thereof;

FIG. 25 is a right side view of FIG. 22 thereof;

FIG. 26 is a left side view of FIG. 22 thereof;
